UNITED STATES PATENT OFFICE.

FREDERICK W. WORLEY, OF MOUNT VERNON, NEW YORK.

ELECTRICAL APPARATUS.

Application filed February 20, 1918, Serial No. 218,231. Renewed March 9, 1922. Serial No. 542,482.

To all whom it may concern:

Be it known that I, FREDERICK W. WORLEY, a citizen of the United States, residing at Mount Vernon, in the county of 5 Westchester and State of New York, have invented certain new and useful Improvements in Electrical Apparatus, of which the following is a specification.

This invention has relation to electrical 10 apparatus, and has for an object to provide a new and improved electrical signal push button.

An object of the invention is to provide a push button of a character comprising 15 but few parts of an inexpensive nature, permitting the devices to be economically manufactured.

A still further object of the invention is to provide a form of push button constructed in a manner to permit the parts to be readily disconnected for repairs, to permit the device to be installed, or for other purposes.

In addition to the foregoing, this invention 25 comprehends improvements in the details of construction and arrangement of parts, to be hereinafter described and particularly pointed out in the appended claim.

The single figure of the drawing is a 30 sectional view.

In the drawing I have shown a base plate 23 of circular configuration formed with a pair of upstruck perforated lugs 23' at diametrically opposite points. A casing 24 35 which is formed of sheet metal is provided for superpositioning upon the base plate and is formed at opposite points with lugs 25 to enter the perforations of the lugs 23' and has the centrally positioned inwardly 40 extending collar 9. The casing is formed to support for sliding movement a button 26 which is provided upon its inner face with a threaded pin 28 on which is held the metallic nut 27.

The pin 28 is guided in an opening in the base plate 23, while the collar 9, slidably 45 holds the member 26.

A circular block of insulating material indicated at 29 has a central opening and 50 rests upon the upper face of the base plate to support a pair of contact plates 30 in end to end arrangement but out of contact. The pin 28 operates between the adjacent 55 ends of the contact plates 30, and a disc of insulating material 31 is secured to the

pin to engage the under sides of the plates to limit the movement of the pin and nut. As shown, the ends of the plates 30 project over the opening in member 29, a coil spring 32 is encircled about the pin and interposed between the disks 31 and the base plate to urge the button in an outward direction. The disc 31 limits the excursion of the button 26.

In my invention the button is depressed 65 until the contact plates 30 are bridged by contact with the nut 27, whereupon the circuit is completed. Bolts 33 serve conjunctively to form binding posts and at the same time secure the contact plates to 70 block 29.

While I have illustrated and described my invention with some degree of particularity, I realize that in practice various alterations may be made therein; and I therefore reserve the right and privilege of changing the form of the details or otherwise altering the arrangement of the correlated parts, without departing from the spirit of the invention or the scope of the 80 appended claim.

Having thus described my invention, what I claim as new and desire to secure by Letters Patent, is:

A device of the character described, a 85 base plate having an opening therein and having apertured ears struck up at opposite sides of said opening, a casing provided with lugs to extend through the apertures of said ears and secure it on said plate, said 90 casing being formed of sheet metal and including an inwardly extending collar, a push button mounted for inward and outward movement in said collar, a pair of contact plates mounted on and insulated from said 95 base plate, said contact plates being spaced from one another, a pin extending through said opening of the base plate and between said contact plates, an insulating member fixed on said pin and normally resting 100 against contact plates, a movable contact fixed on said pin and adapted to be pressed by said button against said contact plates, and a spring compressed between said base plate and insulating member for holding 105 said movable contact normally in spaced relation to said contact plates.

In testimony whereof I affix my signature.

FREDERICK W. WORLEY.
